Attorney, Agent, or Firm—Fitch, Even, Tabin & Flannery

[73] **Assignee:** Comark Merchandising, Inc., Elk Grove Village, Ill.

[57] **CLAIM**

[**] **Term:** 14 Years

The ornamental design for a pivotable display holder for sheets, as shown and described.

[21] **Appl. No.:** 901,933

DESCRIPTION

[22] **Filed:** Aug. 28, 1986

FIG. 1 is a perspective view of a pivotable display holder for sheets showing my new design, it being understood that the broken lines are for illustrative purposes only and form no part of the claimed design; FIG. 2 is a front elevation view thereof; FIG. 3 is a top plan view thereof; FIG. 4 is a rear elevation view thereof; FIG. 5 is a bottom plan view thereof; FIG. 6 is a left side elevation view thereof; and FIG. 7 is a right side elevation view thereof.
